UNITED STATES PATENT OFFICE.

MALCOLM B. MOYER, OF MONTEVIDEO, MINNESOTA.

CATTLE-STANCHION.

1,198,946.

Specification of Letters Patent. Patented Sept. 19, 1916.

Application filed April 26, 1915, Serial No. 23,947. Renewed March 30, 1916. Serial No. 87,853.

To all whom it may concern:

Be it known that I, MALCOLM B. MOYER, a citizen of the United States, residing at Montevideo, in the county of Chippewa and State of Minnesota, have invented certain new and useful Improvements in Cattle-Stanchions; and I do declare the following to be a full, clear, and exact description of the invention, such as will enable others skilled in the art to which it appertains to make and use the same.

This invention relates to cattle stanchions and one object thereof is to so construct a device of this character that it may be readily adjusted for use on cattle of different sizes and in which the parts may be easily taken apart and assembled.

Another object is to provide improved means for detachably connecting the pivot-ed side member of the stanchion in closed operative position.

With the above and other objects in view, the invention consists of certain novel features of construction, combination and arrangement of parts as will be more fully described and claimed.

In the accompanying drawings: Figure 1 represents a side elevation of a stanchion constructed in accordance with this invention and shown in closed position in full lines and in open position in dotted lines. Fig. 2 is an edge view thereof taken from the front; Fig. 3 is a top plan view thereof; Fig. 4 is a longitudinal section through the upper end of the stanchion; Fig. 5 is a transverse section taken on the line 5—5 of Fig. 4; Fig. 6 is a detail sectional view through the hinge of the movable side bar; Fig. 7 is a transverse section taken on the line 7—7 of Fig. 4.

In the embodiment illustrated, this improved stanchion comprises side members 1 and 2 constructed of metal bars U-shaped in cross section with the rounded convex portions thereof disposed inward and which are preferably lined or faced with hard wood strips 3 which are also U-shaped in cross section to conform to the shape of the bars 1 and 2 and which are detachably secured to the inner faces of said bars by bolts having their heads countersunk in said lining members to prevent injury to the neck of the animal and the projecting ends thereof with the nuts thereon are disposed between the side members of the U-shaped bars 1 and 2. These side bars 1 and 2 are connected by cross bars 4 and 5, the bar 4

constituting the upper member or top of the stanchion and the bar 5 the lower member thereof. The stationary side member or 60 bar 1 is connected with the cross bars 4 and 5 by clamps 6 and 7 respectively. The clamp 6 which unites the upper end of bar 1 with the inner or rear end of bar 4 is formed of two plates between which the 65 upper end of bar 1 is disposed and which is secured to said bar by rivets or other suitable fastening elements. These plates 6^a and 6^b are provided on their opposed faces with longitudinally extending grooves 6^c 70 which register with each other when the plates are in assembled position and form a bore to receive the cross bar 4 which is mounted for longitudinal adjustment in said bore and which is secured in adjusted position 75 therein by clamping bolts 8 which pass transversely through flanges 9 formed on the upper or outer edges of the plates 6^a and 6^b, three of said bolts being here shown but it is obvious that any desired number may 80 be employed. When these plates are securely clamped around said bar 4, it will be held reliably in adjusted position. The clamp 7 which connects the lower end of the stationary side bar 1 with the lower 85 cross bar 5, is similar in construction to clamp 6, and the bar 5 is adjustably mounted therein the same as bar 4 is mounted in clamp 6. To adapt these bars to be adjusted to vary the distance between the side 90 bars 1 and 2, the nuts on the bolts 8 are loosened and thereby permit the plates constituting the clamps, to be spread laterally apart a sufficient distance to permit the longitudinal movement between them of 95 said bars 4 and 5 and when these bars have been adjusted to properly position the side members 1 and 2, the nuts are again tightened for holding them in this position.

As shown, the cross bars 4 and 5 are also 100 made U-shaped in cross section with their rounded cross bars or connecting walls disposed inward and which are designed to receive and support the arms of a U-shaped guard 30 which is designed for a purpose 105 to be described. The front end of the upper cross bar 4 is provided on its opposite sides with guides here shown in the form of wings 10 and 11 which are flared outwardly and are designed to receive between them the 110 free end of the movable side member 2. These wings 10 and 11 as shown, are secured to a sleeve 12 which is secured to the free end of the cross bar 4 by a bolt 13 and

this bolt which extends transversely through the side members of the U-shaped cross bar 4 also performs the function of a pintle or pivot for a swinging latch to be described. 5 This sleeve 12 as shown is formed in sections with connecting webs 12' which form corner plates and are riveted together as shown in Fig. 1.

The free end of the movable side bar 2 10 has a laterally extending U-shaped clip 15 secured thereto with the arms thereof opening outwardly and which is designed to be embraced by the wings 10 and 11 when in closed position and when in open position, is 15 adapted to engage a stall partition shown at P for supporting the side bar 2 in partially lowered position ready to receive the head of the animal. The upper edge of this clip 15 between the laterally projecting arms 20 thereof is bent inwardly as shown at 16 to form a catch for engagement by the coöperating latch 14 which is carried by the front end of the bar 4 (see Fig. 4), said latch 14 having a hook-shaped member which engages this forwardly projecting lip 16 and insures a tight grip when the parts are in interlocking position. This latch 14 as 25 shown, is pivoted intermediately of its ends on the rivet 13 between the side walls of the cross bar 4 and a spring 17 is coiled around said rivet with its opposite ends engaging respectively the bottom wall of the cross bar 4 and the rear end of the latch 14 and thus exerts its tension in forcing the hook-shaped 30 front end of said latch into yielding engagement with the lip 16 of the clip 15.

The lower end of the movable side bar 2 is connected with the front end of the bottom cross bar 5 by plates 18 shaped and united 40 to form a sleeve riveted on the front end of said cross bar and provided with laterally spaced wings 19 and 20 between which the lower end of the bar 2 is disposed and pivotally connected therewith by a pivot 21 extending transversely through said bar and wings. A bolt 21' connects the outer ends of the wings 19 and 20 and is designed for limiting the opening movement of the bar 2 when desired but it may be removed to permit the bar 2 to swing down to its full extent.

The U-shaped guard 30 is disposed to one side of the stationary side bar 1 and spaced therefrom with its cross bar disposed vertically and its arms 31 and 32 slidably engaged with the upper and lower cross bars 4 and 5. This member 30 is designed to prevent the animal from dodging the stanchion and placing its head to one side of the bar 1 instead of between the bars 1 and 2. This member 30 as shown, is oval in cross section, being shaped to fit closely between the side member of the U-shaped bars 4 and 5 and to

slide therein to provide for the adjustment of said member 30 toward and away from the bar 1. This member is held in adjusted position relative to the stanchion by means of set screws 33 which extend between the flanges 9 of the clamps 6 and 7 through nuts 34 disposed between said flanges with their inner ends in engagement with the arms 31 and 32 of the guard 30, whereby said arm is securely locked in adjusted position. This stanchion is designed to be held in operative position by means of suspending chains 22 and 23 which are connected respectively with the upper clamping member 6 and the lower clamping member 7 and which are designed to be secured to suitable beams or other supports not shown, in any convenient and well known manner to prevent undue swinging movement of the stanchion proper.

I claim as my invention:—

1. In combination, a stanchion cross bar and longitudinal bar, one of which is movable in relation to the other, outwardly flared wings arranged on opposite sides of one end of said cross bar, a laterally extending U-shaped clip secured to one end of said longitudinal bar with the arms thereof opening outwardly and designed to fit between the wings of said cross bar when the bars are in closed position and to engage a stop when open, the upper edge of said clip between its arms being bent inwardly to form a catch, and a pivoted spring pressed latch carried by said cross bar between the wings thereof and adapted to engage said catch for locking said bars in closed position.

2. In combination, a stanchion cross bar U-shaped in cross section, a sleeve embracing one end of said cross bar, a bolt extending transversely through said sleeve and the arms of said cross bar, a spring pressed latch pivotally mounted on said bolt to swing between the arms of the cross bar, outwardly flared wings arranged on opposite sides of said sleeve, a longitudinal bar pivotally mounted and with its free end movable toward and away from the wing carrying end of said cross bar, a U-shaped clip secured to the free end of said longitudinal bar with the arms thereof opening outwardly and designed to fit between the wings of said cross bar when the bars are in closed position, and a coöperating element carried by said clip for engagement by the latch on the cross bar.

In testimony whereof I have hereunto set my hand in presence of two subscribing witnesses.

MALCOLM B. MOYER.
